UNITED STATES PATENT OFFICE.

THOMAS HOWARD HOLROYD, OF LONDON, ENGLAND, ASSIGNOR OF ONE-HALF TO
ROBERT DONALD DOUGLAS MCLEAN, OF WESTMINSTER, ENGLAND.

APPARATUS FOR GENERATING POWER.

1,355,671.

Specification of Letters Patent.

Patented Oct. 12, 1920.

Application filed April 26, 1917. Serial No. 164,797.

To all whom it may concern:

Be it known that I, THOMAS HOWARD HOLROYD, a subject of His Majesty the King of England, and resident of Northumberland 5 avenue, London, in the county of London, Kingdom of England, have invented certain new and useful Improvements in Internal-Combustion Apparatus for Generating Power, of which the following is a specification.

The present invention relates to improvements in internal combustion apparatus for generating power in combination with a reversible turbine attached or adjoining there- 15 to. The object of my invention is to provide a machine that will be simple in design and construction and easily accessible for repairs.

In the accompanying drawings:

20 Figure 1 is a part sectional and outside general view of the apparatus for generating power.

Fig. 2 is a part sectional and outside general view of the generating apparatus and 25 reversible turbine wheels.

Figs. 3 and 4 are sectional views, on the lines 3—3 and 4—4 respectively, of Fig. 5, of the cut-off valves in the valve blocks.

Fig. 5 is a sectional view of a valve block 30 on the line 2—2 of Fig. 3.

Fig. 6 is a sectional view of a portion of a valve block on the line 6—6, Fig. 3.

Fig. 7 is an extended plan or edge view of 35 part of the periphery of one of the turbine wheels, and

Figs. 8 and 9 are views showing two forms of tappet mechanism suitable for operating the cut-off valves.

According to the form of the invention 40 shown in these drawings, I provide a series of piston heads *a* which are fixed to a circular piston rod *b*. These are inserted into and adapted to reciprocate in a divided, hollow and endless cylinder *c* which is divided 45 into sections by chambered valve blocks *d* which are secured in the said cylinder. The piston heads *a* are provided with expanding rings *e* and, where necessary, the piston heads *a* are made in two halves *a'*, *a''* so as 50 to allow a number of piston heads and valve blocks to be threaded and affixed to the piston rod *b* by known means. The valve blocks *d* for attachment to the cylinder, may also be similarly formed in sections as shown 55 by *d'*, *d''*. The cylinder is divided into two

halves *c'*, *c''* so that the numerous piston heads and piston valve blocks can be assembled *en bloc* in their relative positions, and the parts of the cylinder are fixed together by known means, such as bolts, set screws 60 or the like. The cylinder is water jacketed at *c''*, and the joints are so shaped, grooved, ground, tongued or interlapped as to prevent leakage. In order to obtain the maximum amount of power for a given size of 65 machine I preferably divide the cylinder *c* into eight or more chambers half of which *k*, serve as compression chambers and the other half, *k'*, as combustion chambers by means of eight blocks *d*. The division or valve 70 blocks are formed with reservoirs *d''* to receive compressed charges of air and explosive fluid compressed at each compression stroke, together with a cooling liquid such as water; they also contain the cut-off valves 75 *d''* and *d'''*, shown in Figs. 3, 4, 5, and 6, for controlling the admission of the explosive mixture to the combustion chambers or cylinders *k'*, and the delivery of the heated gases to the turbine. The valve blocks each 80 contain a pair of non-return valves *i* and *i'* which permit the air and fuel to be first drawn into the compression chambers *k* on the induction stroke and, when compressed, to be transferred to the reservoirs *d''* within 85 the blocks. These reservoirs *d''* are provided with spring controlled walls *d''* which yield to the pressure of the compressed mixture and, when the outlet ports are opened, serve to force a mixture of air, fuel and cool- 90 ing liquid into the explosion chambers *k'*. The division or valve blocks *d* are employed in conjunction with valved measuring chambers *g* and *h*, on the outside of the cylinder *c*, for fuel and cooling liquid, respectively, 95 which form the explosive mixture with air drawn in from *f*. These chambers are connected to the valve blocks *d* by suitable conduits *g'* and *h'* and passages *h''*. The circular flat cut-off valves *d''* and *d'''* in each of 100 the blocks *d* are provided with port holes *d''* and *d'''* respectively, which coact to allow the compressed explosive charge to pass from the reservoirs *d''* to the combustion chambers *k'*. The valves *d''* are suitably 105 operated so that the ports *d''* and *d'''* are closed and the ports *d''* in the valves *d''* opened to communicate with the ports *d'''* in the blocks *d*. Between the blocks *d* and the cylinder wall *c* is disposed a sleeve *u* 110

having openings u' and u^2 which coact with conduits u^3 and u^4 connecting with the turbine wheels l through separate pairs of pipes, such as 9, 10, 11 and 12, and inclined nozzles n . One of each of the pairs of pipes 9, 10, 11 and 12, serves for forward driving and the other for reverse driving, and the pairs of pipes 9 and 11 serve the outsides of the wheels and the pairs of pipes 10 and 12 the insides of same. The sleeve u is operated by any suitable means and, as shown in Fig. 3, serves in conjunction with the pipes, to supply a dual control for the turbine wheels l , for the construction is such that when the ports d^8 , d^{10} , u' , and u^3 are in communication with each other the supply of hot exploded gases to the wheels l is through one set of pipes, say the forward pipes of the pairs 9 to 12, for forward driving and when the ports d^8 , d^{10} , u^2 and u^4 are in communication with each other the supply of hot gases to the wheels l is through the other set of pipes, say the rearward pipes of the pairs 9 to 12, for reverse driving. The connections of the hot gas supply pipes with the turbine wheels and the blocks d and the number of such pipes served by each block may vary as desired and in accordance with the number of concentric series of blades provided in each turbine wheel. In the arrangement shown in Fig. 2 each block serves four pairs of pipes and four series of blades on each side of each wheel while the block shown in Fig. 3 is capable of supplying six pairs of pipes which may be connected to the wheels at different points around their peripheries.

The air for each compression chamber passes through the inlet f , the tube f^1 and the valve f^2 , which opens toward the right, into the chamber f^3 under the action of the piston a during the induction stroke of the latter, and fuel is forced by the pump g into said chamber f^3 through the tube g^1 and the non-return valve g^2 which opens toward the left. The fuel passes with the induced air out of the chamber f^3 and through the non-return valve i and the port i^2 into the compression chamber. The outer ends of the chambers f^3 are closed by screw-on caps, not shown. The travel of the pistons h^2 of the chambers h is so adjusted that the amount of cooling liquid forced into the chambers d^3 by the pistons is such that it can be vaporized by the explosions in the combustion chambers and no more.

The valve blocks d are provided with lubricating devices j and the lubricant percolates through suitable conduits not shown, until it reaches the main shaft b through the openings j' .

The turbine wheels l may form part of the multiple compound power generator, and in this case, for convenience, the generator may be incased inside a casing which

could envelop the turbine wheels, thus the delivery of the ejected exhaust gases from the generator would be direct on to the power blades of the turbines through suitable conveyers and inclined nozzles formed in the casings or separately as desired. A rotary or fixed center hollow shaft o is brought through the casing of the turbine wheels and carried by a suitable support, and the turbine wheels revolve with or on the shaft as preferred.

Each turbine wheel preferably comprises radial central web portions p and concentric web portions q to form diamond or box-like sections r from which generate a number of lateral blades or ribs q' . The jets of hot exhaust gases impinge upon these radial ribs and the exhaust gases quickly escape by way of the hollow central shaft o through the holes q^2 and grooves q^3 and downwardly through the hollow passages r' and r^2 as shown by the arrows, thus preventing back pressure. The measuring devices h and g for measuring the cooling liquid and the fuel, respectively, are all provided with adjustable rods or levers and bell cranks as indicated in Fig. 1, and are attached, one to the other, so that the power for operating the several parts is obtained from the piston rod b . The supply of fuel and cooling liquid can be contained within concentrically arranged reservoirs or chambers s and t , disposed around the main shaft o and within the area between said shaft and the hollow endless circular cylinder c . These chambers are connected to the measuring chambers g and h by suitably disposed pipes g^2 and h^3 as shown in Fig. 1. The turbines may be arranged in the center of the generator casing if desired in the place of the reservoirs or chambers s and t .

The operations of the apparatus above described are as follows:—As the pistons 1, 2, 3, and 4 move clockwise to the positions shown in Fig. 1 they draw in air and fuel through the blocks d on their left and through f , g^1 , i and i^2 into the compression chambers h on their left sides, the ports d^8 and d^7 being out of alignment and the ports d^8 and d^{10} in alignment: similarly, as said pistons return and move anticlockwise they draw in a like mixture through the blocks d on their right into said chambers h but on their reverse sides, the ports d^8 , d^7 , d^8 and d^{10} in these blocks being similarly disposed. In both cases, as the pistons move back in either direction after drawing in charges of fuel and air into the chambers h they compress the charges through the ports i^2 and past the valves i' into the reservoirs d^3 , 125 the valve ports d^8 and d^7 and the ports d^8 and d^{10} being, in the meantime, out of alignment. In this manner both sides of each of the pistons 1 to 4 each act to alternately draw in and then compress charges of air 130

and fuel and the four chambers k act as suction and compression chambers on both sides of said pistons.

As the pistons 5, 6, 7, and 8 move clockwise they force and eject the hot gases of charges previously exploded in the combustion chambers k' and on their right sides through the alining ports d^8 and d^{10} in the blocks d on their right and through the connecting pipes and nozzles n to the turbine wheels, the ports d^8 and d^7 being, in the meantime, closed; similarly, as said pistons return and move anti-clockwise they force hot gases from the chambers k' and on their left sides through the blocks on their left, the ports d^8 , d^{10} , d^6 and d^7 in these blocks being similarly disposed. In both cases, when the pistons reach their extreme right or left positions the ports d^8 and d^{10} nearest to them are closed, and the ports d^6 and d^7 are momentarily moved into alinement thus allowing the explosive charges previously compressed in the corresponding reservoirs d^3 to flow, assisted by the spring pressed movable walls d^9 , into the chambers k' . At the same time cooling liquid is forced by the pistons h^2 through h' into the chambers. These compressed charges are then exploded by a correct timing of a suitable ignition mechanism and the pistons are started on their return movements. Directly the pistons begin to move under the influence of the charges exploded on their right or left side the ports d^6 and d^7 in the blocks on that side are closed again, the ports d^8 and d^{10} being out of alinement until the pistons commence their return movements. In this manner both sides of each of the pistons 5 to 8 are each acted upon by an exploded charge and then eject the hot gases on that side, and the four chambers k' act as combustion and exhaust chambers.

The means for operating the movable disk valves d^4 to obtain the proper coöperation of the ports d^6 and d^7 , and the ports d^8 and d^{10} at the correct moments may be of any suitable construction and arrangement, and may include tappet rods b' , Figs. 8 and 9, adapted to be directly or indirectly, operated by the piston heads a . The operative connection between the valves d^4 and the tappet rods b' can partake of any convenient formation, such, for instance, as shown in Fig. 8 or 9. In Fig. 8 the rod b' is provided with inclined surfaces v which coact with a bell-crank lever v' suitably mounted on the valve block and having its lower arm engaging a recess or slot d^{11} in the valve d^4 , to partially rotate the valve first in one direction and then in the other. One of the surfaces v may serve to move the valve d^4 , so that the ports d^6 aline with the ports d^7 , the other surface may serve so that the ports d^8 aline with the ports d^{10} , while the middle position shown in the figure, would be such

that none of the ports would coincide with one another. In Fig. 9 an enlargement v^2 on the rod b' coacts with inclined surfaces v^3 formed on a member d^{10} suitably secured to the valve d^4 . If desired the spindles v^4 of the bell-crank levers v' of Fig. 8 may be extended exteriorly of the cylinder c and carry other bell-crank levers which operate further bell-crank levers and links actuating make and break contacts for the ignition and, also, if desired, insuring simultaneous operation of the valves d^4 in all the blocks d .

What I claim is:—

1. Internal combustion apparatus for generating power, comprising a circular casing, a series of pistons mounted to reciprocate within said casing and secured to a piston rod common to them all, and stationary valve blocks arranged within the casing and between the pistons. 80

2. Internal combustion apparatus for generating power, comprising a circular casing, a series of pistons mounted to reciprocate within said casing and secured to a piston rod common to them all, stationary valve blocks between the pistons, and inlet and outlet valves fitted within said valve blocks. 90

3. Internal combustion apparatus for generating power, comprising a circular casing, a series of pistons mounted to reciprocate within said casing and secured to a piston rod common to them all, valve blocks between the pistons, and fuel and cooling liquid measuring chambers arranged around the casing. 95

4. Internal combustion apparatus for generating power, comprising a circular casing, a series of pistons mounted to reciprocate within said casing and secured to a piston rod common to them all, valve blocks between the pistons, ported coöperating disk valves fitted within said valve blocks, and means for operating certain of said disk valves. 105

5. Internal combustion apparatus for generating power, comprising a circular casing, a series of pistons mounted to reciprocate within said casing and secured to a piston rod common to them all, valve blocks between the pistons, and one or more turbine wheels in communication with the generator formed by the casing, pistons, piston rod and valve blocks. 115

6. Internal combustion apparatus for generating power, comprising a circular casing, a plurality of pistons mounted to reciprocate within said casing and secured to a piston rod common to them all, stationary valve blocks arranged within the casing and between the pistons, reservoirs for compressed charges of explosive mixture and cooling liquid, and inlet and outlet valves fitted within the valve blocks. 120

7. Internal combustion apparatus for generating power, comprising a circular cas- 130

- ing, a plurality of pistons mounted to reciprocate within said casing and secured to a piston rod common to them all, stationary valve blocks arranged within the casing and between the pistons, reservoirs for compressed charges of explosive mixture and cooling liquid, ported coöperating valves fitted within the valve blocks, means for operating certain of said valves, and non-return valves also within the valve blocks.
8. Internal combustion apparatus for generating power, comprising a circular casing, a plurality of pistons mounted to reciprocate within said casing and secured to a piston rod common to them all, stationary valve blocks arranged within the casing and between the pistons, reservoirs for compressed charges of explosive mixture and cooling liquid, ported coöperating valves fitted within the valve blocks, means for operating certain of said valves, and non-return valves and movable explosive mixture and cooling liquid expelling walls also fitted within the valve blocks.
9. Internal combustion apparatus for generating power, comprising a circular casing, a plurality of pistons mounted to reciprocate within said casing and secured to a piston rod common to them all, stationary valve blocks arranged within the casing and

between the pistons, reservoirs for compressed charges of explosive mixture and cooling liquid, ported coöperating valves fitted within the valve blocks, means for operating certain of said valves, non return valves and movable explosive mixture and cooling liquid expelling walls also fitted within the valve blocks, and fuel and cooling liquid measuring chambers communicating with said reservoirs.

10. Internal combustion apparatus for generating power, comprising a circular casing, a plurality of pistons mounted to reciprocate within said casing and secured to a piston rod common to them all, stationary valve blocks arranged within the casing and between the pistons, reservoirs for compressed charges of explosive mixture and cooling liquid, inlet and outlet valves fitted within the valve blocks, a plurality of inclined nozzles connected to the valve blocks, and adapted to direct hot exploded gases on one or more turbine wheels, and ported sleeves which coöperate with certain of said valves whereby the hot exploded gases can pass from the casing and valve blocks to the nozzles and turbine wheel or wheels.

In testimony whereof I have hereunto signed my name.

T. HOWARD HOLROYD.
